(57) **CLAIM**

The ornamental design for label sheet layout assembly, as shown and described.

DESCRIPTION

FIG. 1 is a perspective view of a first embodiment of a label sheet layout assembly showing our new design;

FIG. 2 is a front view of FIG. 1 thereof;

FIG. 3 is a back view of FIG. 1 thereof;

FIG. 4 is a first side view of FIG. 1 thereof;

FIG. 5 is a second side view of FIG. 1 thereof;

FIG. 6 is a top view of FIG. 1 thereof;

FIG. 7 is a bottom view of FIG. 1 thereof;

FIG. 8 is a perspective view of a second embodiment of a label sheet layout assembly showing our new design;

FIG. 9 is a front view of FIG. 8 thereof;

FIG. 10 is a back view of FIG. 8 thereof;

FIG. 11 is a first side view of FIG. 8 thereof;

FIG. 12 is a second side view of FIG. 8 thereof;

FIG. 13 is a top view of FIG. 8 thereof;

FIG. 14 is a bottom view of FIG. 8 thereof;

FIG. 15 is a perspective view of a third embodiment of a label sheet layout assembly showing our new design;

FIG. 16 is a front view of FIG. 15 thereof;

FIG. 17 is a back view of FIG. 15 thereof;

FIG. 18 is a first side view of FIG. 15 thereof;

FIG. 19 is a second side view of FIG. 15 thereof;

FIG. 20 is a top view of FIG. 15 thereof; and,

FIG. 21 is a bottom view of FIG. 15 thereof.

The broken lines in the figures are included for the purpose of illustrating portions of a label sheet layout assembly and do form a part of the claimed design. The first side, second side, top, and bottom views include a shape and appearance that would be evident from the views of the label sheet layout assembly as shown.
